UNITED STATES PATENT OFFICE.

ELIE W. LABOMBARDE, OF NASHUA, NEW HAMPSHIRE.

APPLIANCE FOR MAKING SET-UP BOXES.

Application filed June 15, 1926. Serial No. 116,223.

This invention relates to the manufacture of paper boxes and has particular reference to mechanism for making what are known as set-up or wall boxes, or the covers for such boxes.

Machines which automatically feed blanks and fold them with glue-coated portions pressed together are well known, an example of such machines being illustrated, described and claimed in Letters Patent No. 1,281,982 issued to me October 15, 1918. Such machines are rapid in operation but are expensive and consequently are used only by box makers whose sales are large.

The object of the present invention is to provide, for the use of box makers whose out-put is comparatively small, mechanism which facilitates the completion of boxes most of the folding of which is effected manually. For this reason the mechanism or device referred to herein is termed an appliance instead of a machine.

The invention consists in the construction and combination of parts substantially as hereinafter described and claimed.

Of the accompanying drawings:

Figure 1 is a side elevation of the appliance.

Figures 2 and 3 are similar views illustrating the operation of the appliance.

Figure 4 is a plan view of one form or shape of blank adapted to be operated upon by the appliance.

Figure 5 is a perspective view of a portion of the blank to illustrate the condition or form to which it has been manually folded and ready to be completely folded and pressed by the appliance.

Figure 6 represents a longitudinal section of a box member which has been completed by the appliance.

Similar reference characters designate similar parts in all of the views.

Supported by a suitable base 12 is an upright 13 from which a lateral ledge 14 projects. Rigidly secured to the said ledge is a form block 15 having a slight recess 16 in its upper face. Preferably the form block is removable so that different sizes thereof may be employed according to the work to be done. The outer end of the form block is bevelled rearwardly so that the said block presents an acute angled tip.

Pivoted at 17 to a bracket or lug 18 of the upright 13 is an arm 19 having a form block 20 mounted on its upper end and preferably

removably so for changes of size. The inner face of the form block 20 is bevelled to correspond with the outer face of the stationary block 15. Suitable means are provided to limit the swinging movements of the arm 19, such as a threaded rod 21 projecting from the upright 13 and extending through a hole in the swinging arm, and provided with stop members 22.

Pivoted at 23 to the upright 13 is an arm 24 having a bending member 25 at its outer end, said member preferably consisting of a strip extending transversely of its carrying arm 24. The said arm 24 is normally held by a spring 26 attached to a lug 27 of the upright, in the position indicated in Figure 1, said normal position being determined by a pin 28 of the arm coacting with the upper end of a slot 29 in the upright 13.

Pivoted at 30 to the upright, above the pivot 23 of the arm 24, is a lever 31 having a vertical opening 32 in its forward end for the shank 33 of a presser 34, said shank being preferably so mounted that it can swing or rock somewhat in the opening 32.

The rear end of the lever 31 is connected by a link 35 with a foot lever 36 pivoted at 37 to the lower portion of the upright.

In the use of the appliance illustrated, a blank such as illustrated by Figure 4 is manually moved across a gluing device (a brush or wheel) so as to apply stripes *e* to the end flaps *d*, this kind of work being usually done by girls. Before the glue has time to dry materially, the girl converts one end of the blank to the form illustrated by Figure 5, first bending up the side flap *b*, and turning the two corner flaps *c* toward each other, and then bending or folding the end portion *d* up against the outer faces of the two inwardly folded corner flaps, leaving the glue-carrying flaps *d'* unacted upon. She then mounts the partially hand-folded blank on the form block 20 while the latter is in the outer position illustrated by Figure 1, then depresses the arm 24 so that its strip or blade 25 bends the flap *d'* down as illustrated by Figure 2, then releases the arm 24 and pushes the swinging arm 19 back

by simply pressing against the portion of the blank which covers the outer face of the block 20, this movement of the block 20 causing the downwardly broken or deflected flap *d'* to first engage the angular tip of the stationary block member 15 and then be bent back under the corner flaps *c*, this doubled

portion of the blank then occupying the recess 16 of the block 15. The foot lever 36 is then actuated to cause the presser 34 to be brought down to the position illustrated by Figure 3 and held there for such brief length of time as may be necessary to cause the glue which is carried by the end flap d' to firmly adhere to the corner flaps c which are then between said end flap d' and the portion d .

After one end of the blank has been acted upon as described, the foot lever is released and the presser moves up under the influence of any suitable spring or counterweight which latter may consist of the link 35, the arm 19 is swung out, the box removed from the block member 20 and then the operation described is repeated on the flaps at the other end of the box.

By changes of sizes of the members 15 and 20 which support the box during the pressing and glue-setting operation, the appliance is readily adapted for the making of widely differing sizes or shapes of boxes, deep or shallow.

While I have illustrated the presser as brought into operation by depressing a foot lever, it is to be understood that I do not limit myself thereto. Obviously the presser lever 31 may be actuated by any well-known power mechanism brought into action by a clutch controlled by the foot lever, without departing from the spirit of my invention.

Having now described my invention, I claim:—

1. Mechanism of the character described, comprising a divided support for a box end, one of the members of said support being movable relatively to the other, and a presser movable toward and from the surface of said support.

2. An appliance for making set-up boxes, said appliance having two members for engaging the inner surfaces of overlapping portions of a box, one of said members being movable relatively to the other to provide a space into which a box portion can be bent, means for bending a portion of a box into

such space, and means for exerting pressure on the outer surface of a box mounted on said members.

3. A box-making appliance comprising a stationary block, a second block movable relatively to the stationary block, said blocks having flat upper faces, a flap depresser for acting on a flap of a box when the movable block is displaced, and a presser movable toward and from the faces of said blocks.

4. A box-making appliance comprising a divided support for a box end, one of the members of said support being movable relatively to the other, said other member having an acute-angled tip, and a presser movable toward and from the surface of said support.

5. A box-making appliance comprising a stationary form block, a pivoted arm having a form block at its upper end, a flap bender movable to and from the space between the blocks when they are separated, and a presser movable toward and from the upper faces of said blocks.

6. A box-making appliance comprising a stationary form block having its front face at an acute angle to its upper face, a pivoted arm having at its upper end a form block provided with a rear face at an obtuse angle relatively to its upper face, a flap bender movable to and from the space between the blocks when they are separated, and a presser movable toward and from the upper faces of the blocks.

7. A box-making appliance comprising an upright having a form block projecting from one side thereof, an arm pivotally connected with the upright and having a form block at its upper end, an arm pivoted to the upright and extending over the block projecting therefrom, said arm having a flap-bending member at its outer end, a lever pivotally supported by the upright, and a presser carried by said lever.

In testimony whereof I have affixed my signature.

ELIE W. LABOMBARDE.
